UNITED STATES PATENT OFFICE.

DENNIS LEONARD, OF CLEVELAND, OHIO.

DESIGN FOR A HANDLE-LUG.

SPECIFICATION forming part of Design No. 32,072, dated January 2, 1900.

Application filed December 8, 1899. Serial No. 739,716. Term of patent 7 years.

To all whom it may concern:

Be it known that I, DENNIS LEONARD, a citizen of the United States of America, and a resident of Cleveland, county of Cuyahoga, and State of Ohio, have invented and produced a new and original Design for Handle-Lugs or Coffins or Burial-Caskets, of which the following is a specification, reference being had to the accompanying drawings, forming a part hereof.

In the drawings, Figure I is a front side elevation of a handle-lug embodying my design. Figs. II and III are opposite end elevations of the same.

Two sloping surfaces 5 and 5 are formed upon opposite end portions, respectively, of the lug. The said surfaces extend from or approximately from the upper edge of the lug to or approximately to the lug's lower edge. The said surfaces slope forwardly in the direction of the central portion of the lug, and hence converge in a forward direction. The upper portion of the lug, between the upper ends of the aforesaid sloping surfaces, is convex, as at 6. A recess 7 is formed centrally of and extends between the central portions

of the aforesaid sloping surfaces. The upper side wall of the said recess is formed by the aforesaid upper convex portion of the lug. The lower side wall 8 of the recess slopes forwardly and downwardly. The upper side wall and lower side wall of the said recess diverge, therefore, in a forward direction.

The essential and characteristic features of this design are the two sloping surfaces 35 formed upon opposite end portions, respectively, of the lug and converging forwardly toward the central portion of the lug and extending from or approximately from the upper edge of the lug to or approximately to the 40 lug's lower edge and the recess formed centrally of the lug and extending between the aforesaid sloping surfaces.

What I claim is—

The design for a handle-lug, substantially 45 as shown and described.

Signed by me at Cleveland, Ohio, this 27th day of November, 1899.

DENNIS LEONARD.
